(57) **CLAIM**

We claim the ornamental design for a “filter cartridge with pre-filtration wrap retention through the use of ultrasonic scribing,” as shown and described.

DESCRIPTION

FIG. 1 is side perspective view of the filter cartridge with text wrap retention according to the present invention.

FIG. 2 is left-side view of the filter cartridge with text wrap retention according to the present invention.

FIG. 3 is right-side view of the filter cartridge with text wrap retention according to the present invention.

FIG. 4 is a backside view of the filter cartridge according to the present invention.

FIG. 5 is a top view of the filter cartridge according to the present invention; and,

FIG. 6 is a bottom view of the filter cartridge according to the present invention.

The broken line showing of text in FIGS. 1-3 is included for the purpose of illustrating and forms no part of the claimed design.

1 Claim, 5 Drawing Sheets

FIG. 6

UNITED STATES PATENT AND TRADEMARK OFFICE
CERTIFICATE OF CORRECTION

PATENT NO. : D711,502 S
APPLICATION NO. : 29/447901
DATED : August 19, 2014
INVENTOR(S) : Blake Savoy et al.

Page 1 of 1

It is certified that error appears in the above-identified patent and that said Letters Patent is hereby corrected as shown below:

On the Title Page under item (57), DESCRIPTION (last 3 lines) delete: "The broken line showing of text in FIGS. 1-3 is included for the purpose of illustrating and forms no part of the claimed design."

substitute therefore: "The broken line showing of text in FIGS. 1-3 is included for the purpose of illustrating any insertable text, and the specific text illustrated forms no part of the claimed design."
